UNITED STATES PATENT OFFICE.

EDWARD PERCIVAL, OF PORT HURON, MICHIGAN.

TUMBLER-CLEANER.

SPECIFICATION forming part of Letters Patent No. 278,040, dated May 22, 1883.

Application filed December 8, 1882. (No model.)

To all whom it may concern:

Be it known that I, EDWARD PERCIVAL, of Port Huron, in the county of St. Clair and State of Michigan, have invented new and useful Improvements in Tumbler-Cleaners; and I hereby declare that the following is a full, clear, and exact description thereof, reference being had to the accompanying drawing, which forms a part of this specification.

10 This invention relates to certain new and useful improvements in the construction of devices particularly designed for cleaning tumblers, lamp-chimneys, &c.

The invention consists in the peculiar construction of a cylindrical or conical brush provided with rubber or other suitable wings, which project from two opposite sides of the brush-head, and which describe a circle of greater diameter than that of the bristles or

20 brush proper.

In the accompanying drawing, which forms a part of this specification, A represents the brush-head, which I preferably form in two parts, A' A², and C is the handle. In each 25 portion of the head A, and projecting radially from their respective faces, are the bristles D, which are secured in place by any of the known means. Before the two parts of the head are secured together I place a sheet of rubber or 30 other suitable material between the flat faces

thereof, and then secure the whole together by nails or screws a, with the edges of the rubber projecting slightly beyond the ends of the contiguous bristles, thus forming wings F. Brushes of this character as ordinarily constructed, when dipped in hot water, the bristles become soft, and in frequent use almost worthless, while in this construction I provide a support to the bristles by the introduction of the rubber wings, which also tend to keep the device more central in the tumbler, and act as a scraper to remove matter that has been softened by the water.

What I claim as my invention is—

1. The combination, with a circular brush, 45 of two rubber wings, F, arranged upon opposite sides of said brush and projecting a little beyond the bristles thereof, substantially as described.
2. A device for cleaning tumblers, consisting 50 in the head A, formed of two sections, A' A², rubber wings F, secured between the said sections, and bristles D, all constructed substantially as shown, and for the purposes set forth.

EDWARD PERCIVAL.
